SHOPPING BAG

Joseph O'Meara, St. Paul, Minn.

Application July 19, 1938, Serial No. 220,143

1 Claim. (Cl. 220—84)

This invention relates to bags and particularly to so-called shopping bags.

An object of the present invention is to provide a bag of this character which may be cheaply and economically constructed, and which may be made of light metal or other suitable material.

The invention together with its objects and advantages will be best understood from a study of the following description taken in connection with the accompanying drawings wherein:

Figure 1 is a side elevational view of the bag,
Figure 2 is a top plan view thereof.

Figure 3 is a vertical sectional view through the bag,

Figure 4 is a fragmentary detail view partly in section and partly in elevation showing the manner of attaching the handle to a side wall of the bag, and

Figure 5 is a perspective view of an end portion of the lower longitudinal strip of one of the sides of the bag.

Referring to the drawings by reference numerals it will be seen that in the preferred embodiment thereof my improved bag comprises a pair of opposed side walls 5—5, a pair of end walls 25 6—6, and a bottom wall 7.

The walls 5—5 are each constructed of an upper longitudinal strip 8, a bottom longitudinal strip 9, and an intermediate longitudinal strip 10 together with transverse or vertical strips including intermediate strips 11 and end strips 12.

Strips 11 and 12 are secured to strips 8, 9 and 10 in any suitable manner, as by being adhesively united therewith or otherwise.

Each of the end walls 6 is composed of a vertical series of articulated links or sections including end links 13 which at one end are provided with eyes 14 that engage in eyes 15 provided at the terminals of the strips 8 and 9 and eyes 16 provided at the terminals of the strips 10, together with intermediate links 17 which at their respective opposite ends are provided with eyes with which the inner ends of the links 13 are engaged. Thus it will be seen that a flexible box-like body for the bag is provided.

Also for the bag there is provided a pair of handles, and each handle 17 is substantially U-shaped and has the legs thereof provided with loops 18 that engage in eyes 19 formed integral with the upper edges of the strips 8.

Completing the box-like structure is the aforementioned bottom 7, which like the sides 6, is formed of a plurality of cross strips each of which includes a plurality of articulated links including end links 20 which at one end are provided with eyes or loops 21 that engage integral eyes or loops 22 provided on the lower edges of the side strips 9, and at their inner free ends are provided with

slits 22 to accommodate loops or eyes 23 on the respective opposite ends of intermediate links 24. Thus it will be seen that the bottom, side and end walls of the bag are flexible, thus permitting the entire bag to be reduced to a very small compass. 5

Also for holding the bag in an expanded condition, there are provided at the top of the bag and adjacent the opposite ends of the latter cross bars 25 of some suitable relatively rigid material, and these bars 25 adjacent one end thereof are 10 longitudinally twisted as at 26 and have the twisted ends 26 terminating in eyes or loops 27 that engage eyes or loops 28 provided on the upper longitudinal strip 8 of one of the sides 5. At the free ends thereof the cross bars 29 are provided 15 in the lower edges with slots or notches 29 that receive the upper edge of the strip 8 of the opposite side wall 5 when the bars 25 are disposed transversely of the box. Thus with the bars 25 engaged with the side walls as shown in Figure 3 20 and extending between the side walls said bars serve to prevent undue collapsing of the shopping bag.

It is thought that a clear understanding of the construction, utility and advantages of a shopping bag embodying the features of construction illustrated and described will be had without a further detailed description thereof. 25

Having thus described the invention what is claimed as new is:

A bag of the class described comprising a pair of side members each composed of spaced flat horizontally extending strips, and a plurality of spaced vertically extending flat strips rigidly connected with the horizontal extending strips, said horizontally extending strips including upper, lower and intermediate strips the ends of the horizontally extending strips having vertically elongated eyes formed therein with the eye carrying parts projecting beyond the vertical strips at 30 the ends of the side member, depending lugs carried by the lowermost horizontal strip of each side member, said lugs each having a transversely extending slot therein a bottom member composed of spaced and flat transversely extending strips, 35 each strip consisting of end and intermediate articulated links, the end links having their ends passing through the slots in the depending lugs, with said ends curved around portions of the depending lugs, a pair of end members each formed 40 of spaced and flat strips and each strip consisting of end and intermediate articulated links, the end links having their outer ends passing through the eyes at the ends of the horizontal strips of the side members and bent around portions of said 45 eye forming parts, and handle members connected with the top strips of the side members. 50
